UNITED STATES PATENT OFFICE

HARVEY D. SAMPEY, OF TELFORD, PENNSYLVANIA, ASSIGNOR TO DEXDALE HOSIERY MILLS, OF LANSDALE, PENNSYLVANIA, A CORPORATION OF PENNSYLVANIA

KNITTING MACHINE

Application filed August 19, 1927. Serial No. 214,002.

My invention relates to knitting machines, and more especially to circular knitting machines used in the manufacture of seamless hosiery of the type wherein the legs of the 5 stockings are produced by round and round knitting with all the needles in operation, and the heel and toe pockets by narrowing and widening upon a selected group of needles (usually short butt needles) incidental 10 to oscillation of the needle cylinder, while the remaining needles (long butt needles) are temporarily maintained idle or inactive.

The main object of my invention is to enable, with machines of the kind referred 15 to having but a single set of knitting cams, production of a pair of complementary narrowed tabs in continuation of the stocking foot adapted to be subsequently united by sewing together of their edges to form a 20 tapered toe in lieu of the pocket produced in the ordinary way. This end I attain through a very simple, automatically-operating auxiliary clutch means, whereby, after one of the tabs is knit by fashioning with the 25 short butt needles by oscillatory knitting, the needle cylinder is temporarily detached from the driving mechanism of the machine and subsequently re-coupled therewith after a relative movement of 180°, so that the long 30 butt needles can be acted upon by the knitting cams during further oscillatory knitting to produce the complementary tab.

Another object of my invention is to secure 35 the above advantages with means having the form of an attachment capable of being easily applied to standard knitting machines without involving any serious changes either in their construction or normal mode of operation.

40 In the drawings Fig. I is a side elevation of a circular knitting machine conveniently embodying my improvements.

Fig. II is a plan view of the same with the 45 needle cylinder removed and with certain portions thereof in section in accordance with the arrows II—II in Fig. I.

Fig. III is a linear development of the 50 knitting cams by which the needles are actuated.

Fig. IV is a plan section taken locally as indicated by the arrows IV—IV in Fig. I.

Fig. V is a fragmentary plan section in the same plane as the immediately preceding illustration but with certain parts differently 55 positioned.

Figs. VI and VII are detail cross sections taken locally as respectively indicated by the arrows VI—VI and VII—VII in Fig. IV.

Fig. VIII is a fragmentary perspective 60 view of the needle cylinder and its driving gear wheel.

Fig. IX is a plan section designated by the arrows IX—IX in Fig. I.

Fig. X is a perspective view of the clutch 65 latch by which the needle cylinder is coupled with its driving gear wheel.

Figs. XI and XII are sections taken locally as indicated respectively by the arrows XI—XI and XII—XII in Fig. II, and, 70

Fig. XIII is a perspective view of a stocking toe capable of being produced by the machine improved in accordance with my invention.

The knitting machine chosen for the purposes of illustration herein is of a standard type exemplified in U. S. Patent Nos. 1,266,044 of May 14, 1918, and 1,330,818 of February 17, 1920, both granted to A. M. Pigeon and extensively used in manufacturing seamless hosiery. The needle cylinder 15 of the machine is co-axially mounted on a driving gear wheel 16 (Figs. I, IV, VI and VII) that is recessed in a supporting annulus 17 and retained therein by overlapping washers 17a. 85 This annulus 17 is sustained at the top of a rod 18 having guidance in bearings 19 of the machine frame 20 with capacity for vertical shifting under governance of a rotary cam disc 21 in order to change the level of the 90 needle cylinder 15 with respect to the positionally-fixed knitting cams and thereby vary the size of the fabric loops, as in fashioning the leg of the stocking. These knitting cams are supported on the overhanging 95 portion of the top plate 22 of the machine frame 20 and grouped about the needle cylinder as shown in Figs. I and II. The disc 21 is secured to one end of the shaft 23 in the lower part of the machine frame, which sup-

100

ports the usual clutch control drum 23^a whereby the rotary and oscillatory phases of the knitting operation are determined. The mechanism for driving the machine under 5 these two different conditions includes a pair of spur gears 24—25 which are mounted, for rotation in unison, on a common axis and respectively intermesh with pinions (not shown) on the main driving shaft 26, the latter being equipped, as is generally customary, with high and intermediate speed pulleys 27—28 as well as with a loose pulley 29, see Fig. II. During either phase of operation, the motion received by the main shaft 26 is 10 transmitted, through a pair of companion bevel gears 30—31, to a spur gear 32 that moves with the latter of said bevels, said spur gear 32 in turn imparting motion to the gear wheel 16 at the bottom of the needle 15 cylinder. Intermittent rotary progression of the shaft 23 and the parts carried thereby is governed by a measuring chain 33, all as described in the first of the two Pigeon patents hereinbefore referred to. As is usual with 20 seamless hosiery knitting machines, the cylinder 15 is equipped with two groups of needles, 35—36, which in the present instance, are equal as to number and respectively characterized by long and short butts, the same 25 being distinguished by heavy and light lines in Fig. III. The means for actuating the needles include a pair of stitch cams 37—38 and associate auxiliary cams 37^a, 38^a, the latter cams being yieldingly pressed inwards 30 by springs (not shown) and beveled along their vertical edges as indicated by the line shading in Fig. III, a bottom center cam 39, and side cams 40—41, as well as a cam 42 for elevating the long butt needles 36 to the idle 35 level, preparatory to oscillatory knitting with the short butt needles 36 in forming the heel pockets, and a depressing cam 43 whereby said long butt needles are subsequently returned to the active level. The cam 42 is 40 shaped as shown for the purpose described in the Pigeon Patent #1,330,818 hereinbefore referred to, wherein it is designated by the reference 35 but in the instant case it need only be regarded as a means to raise the long 45 butt needles 35 to inactive level for the purpose of heel and toe fashioning. The needle actuating means further include raising pickers 44—45, and drop pickers 46—47 (Fig. II) to co-operate with said raising pickers alternately during widening incidental to heel knitting. The elevating and depressing cams 42—43 are respectively secured to arms 48—49 which are pivoted intermediate their ends, with capacity for independent swinging movement, on a common fulcrum stud 50 and subject individually to leaf springs 51. During rotary knitting, the elevating and depressing cams 42—43 occupy the positions shown in the drawing; but concurrent with 55 shifting of the main clutch of the machine

(not shown) in changing to the oscillatory phase of operation, their position is reversed, i. e. the elevating cam 42 is permitted to move inward under urging of its spring 51 while the depressing cam 43 is withdrawn. This 70 action is brought about incidental to shifting of the main clutch rod 52 which has attached to it a bracket 53 with inwardly extending fingers 54—55 for engaging studs 56—57 respectively on the cam arms 48—49 at 75 opposite sides of their common pivot 50. The connections at 56—57, it will be observed from Fig. II, allow independent movement of the cams 42—43 as hereinafter more fully explained, in the former instance in opposition to an auxiliary bow spring 58. The bracket 53 also has a finger 59 that normally maintains the elevating picker 44 out of the way of the needle butts during round and round knitting. 80

In converting a machine such as briefly outlined above to the purposes of my invention, I make provisions as follows:

Instead of being rigidly secured to its driving gear wheel 16, the needle cylinder 15 is 90 accorded capacity for independent relative rotary motion under certain conditions hereinafter fully explained. To this end, the upper face of the gear wheel 16 is concentrically recessed as at 60 in Fig. VI to provide a seat for the circumferential flange 61 of a ring 62 that forms a depending axial prolongation of the needle cylinder 15 whereto it is rigidly secured by means of screws 63, 95 retention of the flange 61 within its seat 60 being insured by an overlapping annular plate 64 secured to said gear. Pivoted at 65 to the gear wheel 16 for horizontal swinging movement within a cut-out 64^a of the plate 64, is a clutch latch 66 having the form of a 100 flat arm with a depending lug 67 at its free end adapted to normally occupy one or the other of a pair of diametral notches 68—68^a in the flange 61 of the ring 62, and thus lock the latter (together with the needle cylinder 110 15) for rotation with the gear wheel 16. The clutch latch 66 is yieldingly maintained in the locked position by a leaf spring 69 having anchorage on the annular plate 64 and engaging an upstanding projection or stud 70 of 115 said latch. The means for actuating the clutch latch 66 includes a crescent shaped cam 71 at the end of a curved arm 72 which is fulcrumed at 73 to the lower face of the top plate 22 of the machine frame for movement inwardly from the normal inactive position of Fig. IV to the position of Fig. V with said cam lying against the side of the needle cylinder 15 in readiness to engage the stud 70, thus to withdraw the clutch latch 66 120 temporarily as later on more fully explained. A push bar 74 pivotally coupled at 75 with the arm 72, extends rearwardly along one side of the machine (see Figs. I and II) and has its opposite end resting, with ability to 125 130

slide longitudinally in opposition to a helical tension spring 76, within a notch in the laterally turned extremity 77, of a centrally pivoted lever 78. This lever 78 has fulcrum bearing on a screw 79, let into the side of the machine frame 20, and is subject to a spring 78^a. When in the normal raised position shown in Fig. I, the rear end of the bar 74, lies above the plane of a tappet 80, which is pivoted at 81, for vibration in a horizontal plane, to a lug 82 secured to the side of the machine frame 20. Such movement is constantly imparted to the tappet 80, by virtue of its connection with a reciprocating rod 83, that is supported transversely of the machine frame 20, in suitable bearings of the latter for engagement by a cam 84 on the face of the gear 25, which shifts it in one direction, while a compression spring 85, is relied upon to shift it in the other direction. Any suitable means may be employed to control clutching of the needle cylinder 15, through the coordinated parts just described. For the purpose of exemplification herein, the lever 78, is shown as coupled at 86 with a finger 87, fulcrumed to rock about a fixed axis 88, said finger lying in the path of special cam links 89—89^a on the measuring chain 33. Thus, upon actuation of the finger 87, the lever 78, will be swung downward to bring the end of the push bar 74 into the plane of the oscillating tappet 80, the motion thereby communicated to the latter resulting in inward movement of the cam arm 72, and withdrawal of the clutch latch 66.

In order to check the momentum of the needle cylinder 15 upon withdrawal of the clutch latch 66, I provide a spring brake band 90, (Figs. IV and IX) adapted to clampingly embrace the depending portion of the ring 62 at the bottom of said needle cylinder. The brake band 90 is aligned with a friction strip 91, of leather or asbestos, and has one end secured to a fixed anchorage 92, while its other end is connected at 93 to one extremity of a lever 94 fulcrumed centrally on a stud 95. The opposite extremity of the lever 94 is pivotally coupled at 96, with the slide bar 74, so as to be actuated concurrently with the clutch withdrawal cam arm 72.

For the purpose of bringing down the long butt needles 35 to the active level to enable fashioning with them, the machine is equipped with a lowering cam 97 (see Figs. II, III, and XI), the same being secured to the inner end of a spring influenced rod 98 that is slidable endwise in a bearing bracket 99, but held from rotation by means of a pin 100 projecting through a guide slot 101 in said bearing bracket; while an overhanging guard 97 secured to the bearing bracket 99 serves to direct beneath the cam 97 any long butt needles 35 that may be lifted somewhat above the proper inactive level 65 incident to jarring or otherwise. The cam

97 is controlled by a vertical slide 102 having a bevel 103 which is adapted to cooperate with a collar 104 on the protruding end of the rod 98. This slide 102 is connected, by means of a link 105, to a finger 106 fulcrumed at 107 on the machine frame with its end lying in the path of a laterally projecting lug 108 on the main clutch control drum 23^a, see Fig. I. When engaged, the finger 106 causes downward movement of the slide 102 in opposition to a spring 109, thereby bringing the bevel 103 below the collar 104 and allowing the lowering cam 97 to seek the inner position indicated in dotted lines in Fig. XI under the action of its spring.

As hereinbefore stated during oscillatory knitting with only the short butt needles 36 in operation, the elevating cam 42 is maintained in active position. Now it will be remembered that the cam 42 serves to elevate the long butt needles 35, and must therefore be withdrawn from action when fashioning is practiced with said needles. For this purpose a bolt 110 is provided, see Figs. I, II and XII, the same being slidable vertically in the top plate 22 of the machine frame and having its upper end chamfered so as to be capable, when lifted, of moving the arm 48 and thereby effecting withdrawal of the elevating cam 42. The bolt 110 is held raised by engagement of the arm 48, within an angular recess 111, in its side, and thus serves to temporarily lock the cam 42 in inactive position. The function of elevating the bolt 110, is in the present instance relegated to the lever 78, previously mentioned, see Fig. I.

The operation of the machine is as follows:

Let it be assumed that the cylinder 15 contains two hundred and sixty needles in all, that the heel pocket of a stocking has been knitted in the usual way, and that the machine is just completing the last few rounds of the foot portion F in Fig. XIII immediately previous to change into the oscillating phase of operation for fashioning of the toe. With initiation of the latter operative phase as predetermined in the customary manner by the drum 23^a, the main clutch rod 52 in being incidentally shifted, moves the bracket 53 inward with the result that the depressing cam 43 is withdrawn and the elevating cam 42 at the same time rendered active to raise the long butt needles 35 (constituting one half of the full complement) to the idle level. With ensuing oscillation of the needle cylinder 15, the short butt needles 36 are raised—one at a time—by the pickers 44—45 until but a few (say about thirty needles) remain in action. As a consequence of the procedure just described, a tapered tab such as shown at T in Fig. XIII is produced as a prolongation of one side of

the tubular foot portion F of the stocking. When this is accomplished, the finger 106 is automatically tripped by the projection 108 on the drum 23^a (Fig. I), and the special 5 lowering cam 97 (Figs. II and XI) shifted inward by movement transmitted through the interposed parts previously described, to intercept the long butt needles 35 and bring them all down to the active level. This period in the cycle is graphically depicted in 10 Fig. III from which it will be observed that the current movement of the needle cylinder 15 is to the left and that the long butt needles 35 have just started down the incline of the 15 special cam 97. Contemporaneous with these events, the special lug 89 on the measuring chain 33 engages the finger 87 whereupon the lever 78 is swung to lower the rear end of the 20 push bar 74 into the plane of the tappet 80 for actuation thereby. The forward shog thus communicated to the push bar 74 results in inward movement of the arm 72 to project its cam 71 into the path of the stud 70 on the clutch latch 66 thereby to withdraw the latter 25 momentarily in order to temporarily free the needle cylinder 15. By virtue of its operative co-ordination with the parts just referred to, the brake band 90 is contracted at the same time to arrest the momentum of the needle 30 cylinder 15 which therefore remains quiescent until the latch 66 automatically engages the slot 68^a diametrically opposite the one 68 originally occupied. The needle cylinder 15 thus looses a half rotation to the end that 35 the long butt needles 35 may now be utilized for fashioning purposes. Concurrent with movement of the lever 78 in effecting clutch actuation, it will be observed from Fig. I that the bolt 110 is lifted to withdraw the elevating cam 42 and so hold it temporarily (the cam 43 being already retracted and idle) while narrowing proceeds in precisely the same manner as before, but now with the long butt needles 35 in action to produce the 40 45 complementary tab T¹ of Fig. XIII, the few short butt needles in the group 36^a (Fig. III) previously left at the active level simply moving back and forth with the cylinder 15 at this time without being actuated by the 50 55 stitch cams 37—38 to draw fabric loops since the oscillatory throw imparted to said cylinder by the drive mechanism of the machine is substantially less than a complete revolution. In this connection it is to be remarked that during movement toward the left in Fig. III, needles passing immediately over the top of stitch cam 38 in encountering the beveled vertical edge of the auxiliary cam 38^a, cause the latter cam to be pressed outward. The needles thus pass across the front of this cam 38^a, without being affected by it; but in moving further on are lowered by the auxiliary cam 37^a into the province of the 60 65 stitch cam 37. Similarly, as the needles move in the opposite direction or to the right

in Fig. III, the auxiliary cam 37^a is rendered inoperative while the auxiliary cam 38^a functions to guide the needles to the stitch cam 38. Such action is however characteristic of the standard "Pigeon" knitting machine hereinbefore referred to, and is therefore not, per se, a feature of the present invention. At the end of the second fashioning operation, the finger 87 is tripped again—this time by the lug 89^a of the measuring chain 33, and thereby effects another semi-rotative transposal of the needle cylinder 15 to restore it to the normal operative relation with respect to the knitting cams, whereupon the machine automatically enters into the rotative phase 70 75 80 in the usual manner to start a new stocking. As the bracket 53 (Figs. I and II) is moved inwardly during the last described period in the cycle, the finger 55 in re-engaging the stud 57, imparts slight movement to the arm 85 90 95 100 105 110 115 120 125 130 135 140 145 - gether, and means controlled by the measuring chain aforesaid to actuate the clutch latch in effecting angular positional changes between the needle cylinder and its driving support so that different groups of needles may be acted upon at different times by the fashioning instrumentalities during oscillatory knitting.
4. The combination in a knitting machine embodying a cylinder with needles, a co-axial driving support for the cylinder, means to oscillate the support, fashioning instrumentalities to actuate the needles during oscillatory knitting and a measuring chain; of a pivoted spring pressed clutch latch to normally lock the needle cylinder and its support for movement together, and means controlled by the measuring chain to temporarily withdraw the latch in effecting angular positional changes between said needle cylinder and its driving support so that different groups of needles may be acted upon at different times by the fashioning instrumentalities.
5. The combination in a knitting machine embodying a cylinder with needles, a co-axial driving support for the cylinder, means to oscillate the support, fashioning instrumentalities to actuate the needles during oscillatory knitting and a measuring chain; of clutch means to normally lock the needle cylinder and its support for movement together comprising a spring pressed latch pivoted on the one and adapted to individually engage circumferential notches in the other, and means controlled by the measuring chain to withdraw the latch from one of the notches aforesaid for subsequent engagement with another in effecting angular positional changes between the needle cylinder and its driving support so that different groups of needles are acted upon at different times by the fashioning instrumentalities.
6. The combination in a knitting machine embodying a cylinder with needles, a co-axial driving support for the cylinder, means to oscillate the support, fashioning instrumentalities to actuate the needles during oscillatory knitting and a measuring chain; of clutch means to normally lock the needle cylinder and its support for movement together comprising a spring pressed latch on the one adapted to engage circumferential notches in the other, and a cam projectable into the path of the latch under control of the measuring chain to withdraw said latch from one of the notches aforesaid for subsequent engagement with another in effecting angular positional changes between the needle cylinder and its driving support so that different groups of the needles may be acted upon at different times by the fashioning instrumentalities.
7. The combination in a knitting machine embodying a cylinder with needles, a co-axial driving support for the cylinder, means to oscillate the support, fashioning instrumentalities to actuate the needles during oscillatory knitting and a measuring chain; of clutch means to normally lock the needle cylinder and its support for movement together comprising a spring pressed latch on the one adapted to engage circumferential notches in the other, a cam projectable into the path of the latch to withdraw it from one of the notches aforesaid for subsequent engagement with another in effecting angular positional changes between the needle cylinder and its driving support so that different groups of needles may be acted upon at different times by the fashioning instrumentalities, and automatic means subject to the measuring chain to control actuation of the cam aforesaid.
8. The combination in a knitting machine embodying a cylinder with needles, a co-axial driving support for the cylinder, means to oscillate the support, fashioning instrumentalities to actuate the needles during oscillatory knitting and a measuring chain; of clutch means to normally lock the needle cylinder and its support for movement together, means for actuating the clutch means controlled by the measuring chain to release the cylinder, and concurrently operative means also controlled by the measuring chain to arrest motion of the cylinder temporarily in effecting angular positional changes thereof relative to its driving support so that different groups of needles may be acted upon by the fashioning instrumentalities during oscillatory knitting.
9. The combination in a knitting machine embodying a cylinder with needles, a driving support for the cylinder, means to oscillate the support, fashioning instrumentalities to actuate the needles during oscillatory knitting and a measuring chain; of clutch means to normally lock the needle cylinder and its support for movement together, means controlled by the measuring chain for actuating the clutch means to release the cylinder, and concurrently acting brake band means also controlled by the measuring chain for arresting motion of the cylinder temporarily in effecting angular positional changes thereof relative to its driving support so that different groups of the needles may be acted upon at different times by the fashioning instrumentalities.
10. The combination in a knitting machine embodying a cylinder with needles, a co-axial driving support for the cylinder, means to oscillate the support, and fashioning instrumentalities to actuate the needles during oscillatory knitting; of a clutch latch to normally lock the needle cylinder and its support for rotation together, a cam projectable into the path of the clutch latch to withdraw it temporarily in effecting angular po-

sitional changes between the needle cylinder and its support, a contractile brake band to concurrently arrest motion of the needle cylinder, a thrust bar operatively coordinated with the cam and the brake band, a constantly vibrating tappet, and automatic control means to move the thrust bar into the province of the tappet for projection of the cam to withdraw the latch and at the same time contract the brake band for the purpose aforesaid.

11. The combination in a knitting machine embodying a cylinder with needles, a driving support for the cylinder, means to oscillate the support, fashioning instrumentalities to actuate the needles during oscillatory knitting, and a measuring chain; of a clutch latch to normally lock the needle cylinder and the support for movement together, brake means associated with the needle cylinder, and means controlled by the measuring chain aforesaid to withdraw the clutch latch and concurrently actuate the brake means in effecting angular positional changes between the needle cylinder and its rotating support so that different groups of the needles may be acted upon at different times by the fashioning instrumentalities.

In testimony whereof, I have hereunto signed my name at Lansdale, Pennsylvania, this 15th day of August, 1927.

HARVEY D. SAMPEY.
